ELECTRICAL FUSE

Hugh A. Triplett, Wilmette, Ill., assignor to
Schweitzer & Conrad, Inc., Chicago, Ill., a cor-
poration of Delaware

Original application December 20, 1934, Serial No.
758,372. Divided and this application October
18, 1937, Serial No. 169,612

2 Claims. (Cl. 200—135)

My invention relates, generally, to electrical fuses and it has particular relation to the construction of replaceable fuse links.

This application is a division of my copending application, Serial No. 758,372, filed December 20, 1934, and assigned to the assignee of this application.

The object of my invention, generally stated, is to provide a replaceable spring type fuse link that shall be simple and efficient in operation and which may be readily and economically manufactured and installed.

An important object of my invention is to provide a relatively long length of silver fuse wire for interconnecting a pair of relatively closely spaced infusible terminals of a replaceable spring type fuse link and, at the same time relieve the fuse wire of the spring stress.

Another important object of my invention is to provide for relieving the stress that would otherwise be applied to the fusible element by the spring of a spring type link which is bodily replaceable.

An object of my invention is to coil a fuse wire about the strain wire of a replaceable spring type fuse link.

Other objects of my invention will, in part, be obvious and in part appear hereinafter.

Accordingly, my invention is disclosed in the embodiments hereof shown in the accompanying drawing, and it comprises the features of construction, combination of elements and arrangement of parts which will be exemplified in the construction hereinafter set forth and the scope of the application of which will be indicated in the appended claims.

For a more complete understanding of the nature and scope of my invention reference may be had to the following detailed description taken in connection with the accompanying drawing in which:

Figure 1 is a view, in side elevation, of my improved form of replaceable spring type fuse link;

Figure 2 is a longitudinal sectional view, at an enlarged scale, of the fuse link shown in Figure 1 and illustrating one embodiment of my invention; and

Figure 3 is a fragmentary sectional view, similar to Figure 2, and showing another embodiment of my invention.

Referring now particularly to Figure 1 of the drawing, it will be observed that the reference character 10 designates a replaceable fuse link. This fuse link is of the type that is capable of being used in connection with almost any of the

5 fuse housings that are being sold at the present time. The application of this fuse link to the various types of fuse housings is fully described in the application, referred to hereinbefore, of which this application is a division. Accordingly, a detail description of the application of the replaceable fuse link 10 to various types of fuse housings will not be set forth herein.

The fuse link 10 is replaceable as a unit. It 10 comprises a fuse tube 11, preferably formed of fiber, and it is secured, as will be described hereinafter, at its upper end to a terminal, shown generally at 12. The terminal 12 provides for connecting the fuse link 10 to one line terminal. 15 At its other end, the fuse link 10 is provided with a flexible lead or conductor 13 to permit connection to the other line or circuit terminal. The lower end 14 of the flexible lead 13 is tinned in order to prevent fraying of the strands forming it. Intermediate the ends of the flexible lead or conductor 13 a collar 15 is secured. The collar member 15 is generally tubular in shape and is slipped over the flexible lead 13 to the desired position. It is then flattened, as illustrated, onto the strands forming the flexible lead 13 in order to securely hold it in place. At its lower end the collar member 15 is provided with an integrally formed conical wedging portion 16 to permit connection to certain types of fuse 20 mountings. It will be understood that the replaceable fuse link 10 is ordinarily positioned in a fuse tube and at its upper terminal 12 is connected to one of the circuit terminals. Connection to the other circuit terminal may be provided either by engaging the conical wedging portion 16 in suitable contact means or by connection of the flexible lead 13 to suitable terminals, as desired.

In Figure 2 of the drawing, the details of construction of the fuse link 10 are more clearly illustrated. As there shown the upper fuse link terminal 12 is provided with a threaded stud 19 for threaded engagement with various types of fuse mountings. In order to accommodate other 45 types of fuse mountings a flanged head 20 is screwed onto the threaded end 19. In order to accommodate other types of mounting a dished washer 21, Figure 1, may be provided underneath the flange of the head 20. It will be understood that the upper end of the fuse link terminal 12 may take different forms depending upon the application in which it is to be used. This is more fully described in my copending application, mentioned hereinbefore, of which this 50 application is a division.

The terminal 12 may be machined from a suitable rod such as a rod of brass or copper the initial diameter of which is indicated by the flange 22 intermediate its ends. The upper end is reduced in diameter and threaded as indicated at 19. Just below the flange 22 a circumferential groove 23 is provided into which the upper end of the fiber fuse tube 11 may be pinched as indicated at 24. By securing the upper end of the fuse tube 11 as indicated, relative longitudinal movement with the terminal 12 is prevented. In order to prevent relative turning between the terminal 12 and the fuse tube 11, the terminal 12 is provided with a knurled portion 25. When the upper end of the fuse tube 11 is pinched into the groove 23, the edges of the knurled portion 25 bite into the inner surface of the fuse tube 11 and securely hold it in place.

The lower end of the fuse terminal 12 is provided with a reduced portion 26 having an axially drilled aperture therein for receiving the composite fusible element, shown generally at 27. As indicated the composite fusible element 27 comprises a strain wire 28 and a fuse wire 29. The strain wire 28 is preferably formed of high tensile strength wire, such as nickel-chromium wire while the fusible element 29 is preferably formed of silver. In this embodiment of the invention it will be observed that the silver fuse wire 29 is wrapped in an open spiral about the strain wire 28.

The composite fusible element 27 comprising the strain wire 28 and the fuse wire 29 are inserted in the axially drilled aperture in the lower reduced portion 26 of the terminal 12 and then it is deformed onto them. This is done by flattening the opposite sides to provide the construction shown. In order to further provide engagement between the strain and fuse wires 28 and 29, the flattened portion 26 is locally deformed, as indicated at 30, by a suitable tool, such as a punch, so that the strain and fuse wires are securely held in place.

At its lower end the composite fusible element 27 is secured in the upper end portion 33 of a lower fuse terminal, shown generally at 34. The terminal 34 is initially generally tubular in shape and is adapted to receive the lower ends of the strain and fuse wires 28 and 29. The upper end portion 33 is flattened onto the ends of the strain and fuse wires therein and is further locally deformed, as indicated at 35, for securely holding them in position. It will be understood that the deforming of the terminal portions 26 and 33 onto the ends of the strain and fuse wires 28 and 29 and then the locally deforming of them, as indicated at 30 and 35, not only provides for securing these wires in position but also insures good electrical connection thereto. This is important in fuse link construction.

The lower end 33 of the lower fuse terminal 34 is flattened onto the upper end of the portion 37 of the flexible lead 13 which extends into the fuse tube 11. It will be observed that the portion 36 is flattened substantially at right angles to the upper portion 33. This construction facilitates the connection of the coil tension spring 38, the upper convolutions of which surround the portion 36 and the extreme upper convolution being reduced about the shoulders formed at the junction with the upper portion 33.

The lower fuse terminal 34 is formed of copper or brass. Since the portions 26 and 33 of the fuse terminals 12 and 34, respectively, adjacent the composite fusible element 27 comprising the

strain wire 28 and fuse wire 29, are relatively massive as compared to the fusible element 27, they may be considered as being relatively infusible. When the fuse link is called upon to operate for the purpose of opening the circuit on the occurrence of a fault, only fuse wire 29 and the strain wire 28 are melted in the order named. The arc that is then formed is confined between the portions 26 and 33 of the terminals 12 and 34. Since they are relatively infusible little, if any, metal from them is vaporized by the heat of the arc with the result that the likelihood of the formation of a metallic vapor path for sustaining the arc is appreciably reduced. This is particularly true when the strands of the flexible lead 13 are taken into consideration. If the strain and fusible wires 28 and 29 were secured directly to the upper end of the section 37 of the flexible lead 13 which extends into the fuse tube 11, it is quite likely that considerable portions thereof would be vaporized due to the heat of the arc. This condition is obviated by the provision of a definite metallic barrier between the fusible element 27 and the flexible lead 13. As indicated, this is provided by the lower fuse terminal 34 which is relatively massive and relatively infusible.

As indicated hereinbefore a coil tension spring 38 is provided and its upper end is attached to the lower fuse terminal 34. The spring 38 is provided for separating the terminal 34 from the terminal 12 when the fusible element 27 blows. It is arranged to apply a predetermined tension to the fusible element 27. Since the strain element 28 provides a direct mechanical connection between the fuse link terminals 12 and 34 while the fuse wire 29 is coiled about the strain wire 28, the latter is relieved of any mechanical stress which would otherwise be imposed by the spring 38. At the same time a relatively long length of fuse wire 29 is provided between the closely spaced terminals 12 and 34 as will be readily apparent. Such length of fuse wire is desirable in order to provide the desired time-current fusing characteristics of the fusible element 27.

At its lower end the spring 38 is secured to a collar 39 that is flattened onto the lower end of the portion 37 of the flexible lead 13. It will be observed that the lower end of the fuse tube 11 is closed by an anchor plate 40 having a centrally located aperture 41 through which the flexible conductor 13 projects. The upper end of the collar member 39 abuts the under surface of the anchor plate 40 and thereby resists the stress imposed by the coil spring 38. It will be observed that the spring 38 does not apply any tension to the portion 37 of the flexible conductor 13 between the fuse terminal 34 and the collar 39. Any desired tension may be applied to the flexible lead 13 externally, either by springs in the housing or by the lineman in refusing the housing, without imposing on the strain wire 28 any stress in addition to that already imposed by the spring 38 unless this stress imposed by the spring 38 is exceeded. This type of spring arrangement and fastening therefor provides a non-cumulative type of replaceable spring link. It constitutes a distinct advance in the art. However, the non-cumulative arrangement of the spring 38 forms no part of my invention. It is disclosed and claimed in the copending application of Lindell, Serial No. 70,280, filed March 23, 1936, and assigned to the assignee of this application.

In Figure 3 of the drawing I have illustrated a replaceable type of spring link that is generally similar to the link shown in Figures 1 and 2 of the drawing and described hereinbefore. The difference resides in the construction of the composite fusible element 27'. As illustrated, the fuse wire 29', preferably formed of silver, is coiled in an open spiral about the strain wire 28 but, in this embodiment, the convolutions are spaced from the strain wire 28 rather than being in close engagement therewith as is the case with the fuse wire 29 as shown in Figure 2. When the fuse wire 29' is spaced away from the strain wire 28, its time-current characteristic can be more accurately predetermined than is the case with a construction shown in Figure 2 since no heat generated therein is conducted therefrom directly by the strain wire 28.

When the fuse wire 29' is spaced from the strain wire 28 it serves another useful function. Because of the relatively large effective diameter of the coil 29 as compared to the diameter of the strain wire 28 the effects of corona are materially reduced.

Since certain further changes may be made in the above constructions and different embodi-

ments of the invention may be made without departing from the scope thereof, it is intended that all matters contained in the above description or shown in the accompanying drawing shall be interpreted as illustrative and not in a limiting sense.

I claim as my invention:

1. A fuse link comprising, a pair of terminals, a fusible element in the form of a wire connecting said terminals, a strain wire also interconnecting said terminals, said fusible element being wound upon the strain wire in definite contact with the same, a sleeve of insulation enclosing said element and wire, and a spring carried by the link, said spring being normally under stress tending to separate said terminals.

2. A fuse link comprising, a pair of terminals, a fusible element in the form of a wire connecting said terminals, a strain element also interconnecting said terminals, said fusible element being wound in definite contact engagement around said strain element, and a sleeve of insulation enclosing said fusible and strain elements.

HUGH A. TRIPPLETT.
